UNITED STATES PATENT OFFICE.

EDGAR H. COTTRELL, OF NEW YORK, N. Y., ASSIGNOR TO C. B. COTTRELL & SONS COMPANY, OF NEW YORK, N. Y., A CORPORATION OF NEW JERSEY.

PRINTING-MACHINE.

1,072,703.

Specification of Letters Patent.

Patented Sept. 9, 1913.

Application filed June 21, 1912. Serial No. 705,068.

To all whom it may concern:

Be it known that I, EDGAR H. COTTRELL, a citizen of the United States, and resident of the borough of Manhattan, in the city and 5 State of New York, have invented a new and useful Improvement in Printing-Machines, of which the following is a specification.

This invention relates to printing machines and is directed particularly to shifting tympan holding devices.

The object of this invention, broadly considered, is to provide means for subjecting a plurality of shifting tympans to variations in pressure, whereby they will be effected by one pressure while in their fixed positions and by another pressure during their shifting operation.

More specifically considered, the invention contemplates the provision of mechanism for holding one or more tympans tightly against the cylinder by suction for a predetermined number of revolutions while its or their surface or surfaces are 25 printing, and for blowing the said tympan or tympans away from the cylinder during its or their shifting operation; whereby the tympans are prevented from slipping when in their fixed positions while the shifting 30 thereof is materially facilitated.

A practical embodiment of my invention is represented in the accompanying drawings, in which—

Figure 1 represents an end view (parts 35 being removed) of a portion of an impression cylinder and frame showing the tympan shifting mechanism and part of the mechanism for controlling the pressure on the tympans, together with the compressed 40 air tank and suction pump, Fig. 2 represents a side view of the same and adjacent parts for carrying out this invention, portions being broken away to more clearly show the parts beneath, Fig. 3 represents a 45 detail section taken in the plane of the line A—A of Fig. 2, looking in the direction of the arrows, Fig. 4 represents a detail section taken in the plane of the line B—B of Fig. 2, looking in the direction of the arrows, parts being broken away, Fig. 5 represents 50 a detail section taken in the plane of the line C—C of Fig. 4, looking in the direction of the arrows, without the parts broken away, Fig. 6 represents a section 55 taken in the plane of the line D—D of Fig.

2, looking in the direction of the arrows, and Fig. 7 represents a detail section showing one of the grooves in the cylinder for subjecting the tympans to variations in air pressure.

The impression cylinder is denoted by 1 and its shaft by 2, which latter is journaled in a suitable frame 3. The usual blankets 4 are interposed between the surface of the cylinder and the shifting tympans 5; and 60 well known mechanism is provided for periodically shifting the tympans. The particular form of said shifting mechanism, illustrated in the accompanying drawings, is shown in United States Letters Patent 70 No. 996902, granted to H. M. Barber, July 4, 1911, and hence will not be described herein as its specific form constitutes no part of the present invention.

The periphery of the cylinder 1 is provided at desired intervals throughout its length, for instance at points where they will engage the tympans in line with the margins on the printed sheets, with laterally disposed segmental passages 6, each of 75 said passages being covered by a plate 7 set flush with the surface of the cylinder and provided with a longitudinal series of 80 perforations 8. By virtue of the location of the passages 6 and perforated plates 7, 85 the creation of a partial vacuum within one or more of the said passages, will draw one or more tympans tightly against the surfaces of the cylinder, and when, on the other hand, the air pressure is raised above 90 normal within one or more of said passages, the air passing through the perforations 8 will serve to blow the tympans away from their engagement with the cylinder.

The hub of the cylinder 1 is provided 95 with four longitudinally disposed bores 9 parallel with respect to the axis of the cylinder, which bores are open at one end of the cylinder for communication with four passages 10 in the valve seat 11 which 100 is arranged to rotate with the cylinder 1. These passages 9 are connected by means of radial passages 9* with the segmental passages 6 in the periphery of the cylinder 1.

Four radially acting slide valves 12 are 105 mounted on the valve seat 11 with their ports 13 in alignment with the passages 10, in the valve seat 11, the said valves being held in operative position by the port disk 14, which is secured to the seat 11 by bolts 110

15. This disk 14 is provided with eight short arcuate ports 16 arranged in sets of four at different radial distances from the axis of the cylinder 1, the said ports being adapted to register with the ports 13 in the valves 12.

16. A port ring 17 is secured against rotation on the frame 3, which ring is provided with inner and outer segmental port chambers 18 and 19, respectively; the said inner 10 chamber 18 being so radially located as to register with the inner set of ports 16 in the port disk 14; while the outer chamber 19 is arranged to register with the outer set of ports 16 in the port disk 14. The inner 15 port chamber 18 has an open communication with a hollow boss 20 located on the periphery of the port ring 17; while the outer port chamber 19 is correspondingly in communication with a similar hollow boss 21 also located on the periphery of the port ring 17 in diametric opposition to the boss 20.

17. The slide valves 12 have a pivoted engagement at their outer portion with one 25 end of a bell crank 22 which is centrally pivoted at 23 in a lug 24 on the valve seat 11; the other extremity of the bell crank 22 having a pivotal engagement at 25 with a laterally extending spur on a rocking 30 pawl lever 26 which is fulcrumed at 26*. This rocking pawl lever 26 is part of the tympan shifting mechanism shown in United States Letters Patent No. 996,902 referred to above, and is acted upon at one end by 35 an expansion spring 27 for normally holding its pawl teeth 28 in engagement with the ratchet wheel 29, while the usual circular track 30 serves to engage the shoe 31 at periodic intervals for disengaging the pawl 40 lever 26 from the ratchet 29 during the shifting of the tympan.

18. The hollow boss 21 on the port ring 17, which is in communication with the outer port chamber 19, is connected by means of 45 a pipe 32 with a source of compressed air 33; while the oppositely disposed hollow boss 20 is connected by means of a pipe 34 with an exhaust pump or fan 35, which exhaust pump is connected with the compressed air tank 33 by a pipe 36. The pipe 34 is provided with a suction valve 37 so that the vacuum pump 35 may suck in air when communication is cut off between the pipe 34 and the passages 6 in the cylinder 1.

50. The valve seat 11 and port disk 14 are secured to the cylinder 1 and rotate therewith; while the port ring 17 is secured to the frame 3 by the pipes 32 and 34 passing in to the bosses 20, 21, and expansion 55 springs 38, surround the pipes 32 and 34 between the frame 3 and the bosses 20 and 21 for firmly holding the port ring 17 against the port disk 14 on the cylinder 1.

56. The operation of the device is as follows: 60 When a tympan is about to be shifted, the

circular track 30 engages the shoe 31 on the rock pawl lever 26 thereby rocking the said lever and disengaging the teeth 28 from the ratchet wheel 29. This rocking of the lever 26 also rocks the bell crank 22 about its pivot 23 and causes the corresponding valve 12 to be moved radially away from the axis of the cylinder, until its port 13 registers with the proximate end 19* of the port chamber 19 in the valve ring 17 thereby opening communication from the source of compressed air 33 through the pipe 32, hollow boss 21, port chamber 19, outer port 16, port 13, passage 10, passage 9, and passages 9*, to the segmental passages 6 in the appropriate quadrant of the cylinder 1, thus permitting the compressed air to spurt through the holes 8 in the plate 7 and below the corresponding tympans away from the surface of the cylinder, for facilitating the shifting of the said tympans. The shifting of the tympan takes about half a revolution of the cylinder 1, so that at the time the tympan mechanism is about to tighten the tympan again on the cylinder, the port 13 in the valve 12 is moving off of the other end of the port chamber 19 thus closing off the communication from the source of compressed air 33 to the passages 6, and hence permitting the tympan tightening mechanism to readily tighten the tympans on the cylinder. This actuation of the tympan tightening mechanism results from the disengagement of the circular track 30 and the shoe 31 whereby the spring 27 may force the teeth 28 on the lever 26 into engagement with the ratchet wheel 29. This movement of the pawl lever 26 by the spring 27 also rocks the bell crank 22 so as to force the corresponding slide valve 12 inwardly thus bringing its port 13 at the same radial distance from the center of the cylinder 1 as the port chamber 18 in the port ring 17. This inward movement of the valve 12 occurs during the time the cylinder is rotating through the arc between the tail end of the port chamber 19 and the front end 18* of the port chamber 18. Hence, as the cylinder continues its rotation with the corresponding tympans tightened thereon, the port 13 in the valve 12 comes opposite the end 18* of the port chamber 18 thereby opening communication from the exhaust fan or pump 35, through the pipe 34, hollow boss 20, port chamber 18, inner port 16, port 13, passage 10, port 9 and passages 9*, to the segmental passages 6 in the periphery of the cylinder 1, thus causing a partial vacuum in the passages 6. The difference in pressure against the tympan caused by this partial vacuum holds the tympan tightly against the surface of the cylinder during the printing operation, or until it is again time to shift the said tympan.

It will be understood that the above description refers merely to one quadrant of the cylinder 1 and its corresponding tympan. A similar operation occurs in exactly a similar manner for the tympans on each ninety degrees of the cylinder 1.

By the arrangement above described, I have provided mechanism for firmly holding tympans in place during the printing operations and for greatly facilitating the shifting of the said tympans, which mechanism is simple and is automatically controlled by the mechanism which shifts the tympans.

It is to be understood that perforations corresponding to the holes 8 in the plates 7 are formed through the blankets or in packing that may be on the cylinder under the tympans so as to insure the subjection of the tympans to the suction and blowing action hereinabove described. It will also be understood that various changes may be made in the form, construction and operation of the several parts without departing from the spirit and scope of my invention; hence I do not wish to limit myself strictly to the structure herein set forth, but

What I claim is:—

1. In combination, a cylinder, a plurality of tympans thereon, and a common means for holding the tympans against the cylinder by suction.

2. In combination, a cylinder, a plurality of shifting tympans thereon and a common means for holding the tympans against said cylinder by suction.

3. In combination, a cylinder, a plurality of tympans thereon and a common tympan holding device comprising an exhaust pump and means for automatically bringing the exhaust pump into and out of operative relation with respect to the tympans.

4. In combination, a cylinder, a plurality of shifting tympans thereon, and a common tympan holding device comprising an exhaust pump and means for automatically bringing the exhaust pump into and out of operative relation with respect to the tympans.

5. In combination, a cylinder, a shifting tympan thereon and means for subjecting the tympan to one pressure while fixed and to another pressure when shifting.

6. In combination, a cylinder, a plurality of shifting tympans thereon and means for subjecting the tympans to one pressure while fixed and to another pressure when shifting.

7. In combination, a cylinder, a shifting tympan thereon and means for subjecting the tympan to suction while fixed and for removing the suction when shifting.

8. In combination, a cylinder, a plurality of shifting tympans thereon and means for subjecting the tympans to suction while fixed and for removing the suction when shifting.

9. In combination, a cylinder, a shifting tympan thereon, and means for blowing the tympan away from the cylinder during the shifting operation.

10. In combination, a cylinder, a plurality of shifting tympans thereon and means for blowing the tympans away from the cylinder during the shifting operation.

11. In combination, a cylinder, a plurality of shifting tympans thereon, and a common means for blowing the tympans away from the cylinder during the shifting operation.

12. In combination, a cylinder, a shifting tympan thereon, and means for holding the tympan against the cylinder by suction and for blowing the tympan away from the cylinder during the shifting operation.

13. In combination, a cylinder, a plurality of shifting tympans thereon and means for holding the tympans against the cylinder by suction while fixed and for blowing the tympans away from the cylinder when shifting.

14. In combination, a cylinder, a shifting tympan thereon and a tympan holding device comprising an exhaust pump, a compressed air tank, and means for automatically bringing the one or the other into operative relation with respect to the tympan.

15. In combination, a cylinder, a shifting tympan thereon and a tympan holding device comprising a perforated tube on the periphery of the cylinder under the tympan, an exhaust pump and means for automatically bringing the pump into and out of communication with said perforated tube at predetermined intervals.

16. In combination, a cylinder, a shifting tympan thereon and a tympan holding device comprising a perforated tube on the periphery of the cylinder under the tympan, an exhaust pump, a compressed air tank and means for automatically bringing the one and the other into and out of communication with said perforated tube at predetermined intervals.

17. In combination, a cylinder, a plurality of shifting tympans thereon and a tympan holding device comprising an exhaust pump and means for automatically bringing the exhaust pump into operative relation with respect to each of the said tympans.

18. In combination, a cylinder, a plurality of shifting tympans thereon and a tympan holding device comprising an exhaust pump, a compressed air tank and means for automatically bringing the one or the other into operative relation with respect to each of the said tympans.

19. In combination, a cylinder, a plurality of shifting tympans thereon and a tympan holding device comprising perforated passages in the periphery of the cylinders under the tympans, an exhaust pump and

means for automatically bringing the pump into and out of communication with said perforated passages at predetermined intervals.

- 5 20. In combination, a cylinder, a plurality of shifting tympans thereon and a tympan holding device comprising perforated passages in the periphery of the cylinder under the tympans, an exhaust pump, a compressed air tank and means for automatically bringing the one and the other into and out of communication with said perforated passages at predetermined intervals.
- 15 21. In combination, a cylinder, a shifting tympan thereon and means for subjecting the tympan to one pressure during a predetermined number of revolutions of the cylinder while the tympan is fixed and to another pressure while the tympan is shifting.

22. In combination, a cylinder, a plurality of shifting tympans thereon and means for subjecting each of the tympans to the one pressure during a predetermined number of revolutions of the cylinder while the tympan is fixed and to another pressure while the tympan is shifting.

23. In combination, a cylinder, a shifting tympan thereon and means for subjecting the tympan to suction during a predetermined number of revolutions of the cylinder while the tympan is fixed and for removing the suction while the tympan is shifting.

24. In combination, a cylinder, a plurality of shifting tympans thereon and means for subjecting each of the tympans to suction during a predetermined number of revolutions of the cylinder while the tympan is fixed and for removing the suction while the tympan is shifting.

25. In combination, a cylinder, a shifting tympan thereon and means for blowing the tympan away from the cylinder every predetermined number of revolutions of the cylinder during the shifting operation.

26. In combination, a cylinder, a plurality of shifting tympans thereon and means for blowing each of the tympans away from the cylinder every predetermined number of revolutions of the cylinder during the shifting operation.

27. In combination, a cylinder, a shifting tympan thereon and means for subjecting the tympan to suction for a predetermined number of revolutions of the cylinder while the tympan is fixed and for blowing the tympan away from the cylinder when the tympan is shifting.

28. In combination, a cylinder, a plurality of shifting tympans thereon and means for subjecting each of the tympans to suction for a predetermined number of revolutions of the cylinder while the tympan is

fixed and for blowing each of the tympans away from the cylinder when the tympan is shifting.

29. In combination, a cylinder, a tympan thereon, means for automatically shifting the tympan every predetermined number of revolutions of the cylinder and means controlled by the tympan shifting means for subjecting the tympan to one pressure while the tympan is fixed and to another pressure while the tympan is being shifted.

30. In combination, a cylinder, a plurality of shifting tympans thereon, means for automatically shifting the tympans every predetermined number of revolutions of the cylinder and means controlled by the tympan shifting means for subjecting the tympans to one pressure while the tympans are fixed and to another pressure while the tympans are being shifted.

31. In combination, a cylinder, a tympan thereon, means for automatically shifting the tympan every predetermined number of revolutions and means controlled by the tympan shifting means for subjecting the tympan to suction while the tympan is fixed and for removing the suction while the tympan is being shifted.

32. In combination, a cylinder, a plurality of tympans thereon, means for automatically shifting the tympans every predetermined number of revolutions of the cylinder and means controlled by the tympan shifting means for subjecting the tympans to suction while the tympans are fixed and for removing the suction while the tympans are being shifted.

33. In combination, a cylinder, a tympan thereon, means for automatically shifting the tympan every predetermined number of revolutions of the cylinder and means controlled by the tympan shifting means for blowing the tympan away from the cylinder when the tympan is being shifted.

34. In combination, a cylinder, a plurality of tympans thereon, means for automatically shifting the tympans every predetermined number of revolutions of the cylinder and means controlled by the tympan shifting means for blowing the tympans away from the cylinder when the tympans are being shifted.

35. In combination, a cylinder, a tympan thereon, means for automatically shifting the tympan every predetermined number of revolutions of the cylinder and means controlled by the tympan shifting means for subjecting the tympan to suction while the tympan is fixed and for blowing the tympan away from the cylinder when the tympan is being shifted.

36. In combination, a cylinder, a plurality of tympans thereon, means for automatically shifting the tympans every predetermined number of revolutions of the

cylinder and means controlled by the tympan shifting means for subjecting the tympans to suction while the tympans are fixed and for blowing the tympans away from the cylinder when the tympans are being shifted.

In testimony, that I claim the foregoing

as my invention, I have signed my name in presence of two witnesses, this eighteenth day of June 1912.

EDGAR H. COTTRELL.
